US00D459355S

(12) **United States Design Patent** (10) Patent No.: **US D459,355 S**
Shimoda et al. (45) Date of Patent: ** Jun. 25, 2002

(54) **IC MEMORY CARD**

(75) Inventors: **Kenji Shimoda; Shinichi Hiroki**, both of Tokyo; **Takashi Torii; Yutaka Nakamura**, both of Kadoma, all of (JP); **Bob Wallace**, Sunnyvale, CA (US); **Dan Auclair**, Sunnyvale, CA (US); **Yoram Cedar**, Sunnyvale, CA (US); **Yosi Pinto**, Tefen (IL)

(73) Assignees: **Kabushiki Kaisha Toshiba**, Tokyo (JP); **SanDisk Corporation**, Sunnyvale, CA (US); **Matsushita Electric Industrial Co.**, Osaka (JP)

(**) Term: **14 Years**

(21) Appl. No.: **29/148,140**

(22) Filed: **Sep. 17, 2001**

(30) **Foreign Application Priority Data**

Mar. 16, 2001 (JP) 2001-007025

(51) LOC (7) Cl. **14-02**

(52) U.S. Cl. **D14/436**
